(57) **CLAIM**

The ornamental design for an automobile side aero feature or replica thereof, as shown and described.

DESCRIPTION

FIG. 1 is a front, left perspective view of an embodiment of an automobile side aero feature or replica thereof in accordance with the present design;

FIG. 2 is a rear, left perspective view of FIG. 1;

FIG. 3 is a left elevation view of FIG. 1;

FIG. 4 is a right elevation view of FIG. 1; and,

FIG. 5 is an enlarged view of a portion of FIG. 1.

Portions of the automobile side aero feature or replica thereof shown in evenly spaced broken lines depict environmental structures that form no part of the claim. The dot-dash broken lines in FIGS. 1 and 5 illustrate the periphery of the enlarged views of the automobile side aero feature or replica thereof and form no part of the claimed design.
